UNITED STATES PATENT OFFICE.

WILLIAM THOMAS FREE, OF CHATTANOOGA, TENNESSEE.

ACETYLENE-GAS BURNER.

SPECIFICATION forming part of Letters Patent No. 740,750, dated October 6, 1903.

Application filed June 24, 1903. Serial No. 162,931. (No model.)

To all whom it may concern:

Be it known that I, WILLIAM THOMAS FREE, a citizen of the United States, residing at Chattanooga, in the county of Hamilton and State 5 of Tennessee, have invented a new and useful Acetylene-Gas Burner, of which the following is a specification.

This invention relates to acetylene-gas burners.

In the consumption of acetylene gas for lighting purposes great difficulty is found in preventing the accumulation of carbon at the burner-tip and the choking of the gas-passage from this cause. To effect thorough 15 combustion, the quantity of atmospheric air admixing with the gas must be in exact proportion to the quantity of gas passing through the tip, and carbon will be liberated and deposited in the form of soot if the quantity of 20 air is too small or too large, a large quantity of air cooling the flame, while a small quantity results in imperfect combustion. For these reasons it is found practically impossible to employ an ordinary form of burner for 25 lighting purposes, especially in house systems, where at times it becomes desirable to lower the flame as a matter of economy. The ordinary acetylene-gas burners are proportioned with a view of properly burning a constant 30 quantity of gas, generally from so-called "self-generating" lamps, where the gas is continuously manufactured so long as a quantity of water is admitted to the carbid or where quantities of carbid are gradually fed to a 35 body of water. Devices of this class have no means for regulating the quantity of gas passing from the generator-tank to the burners, the regulating devices employed controlling only the supply of carbid or of water; but in 40 house systems the distribution of the gas is carried on in a manner somewhat similar to the distribution of ordinary coal or oil gas, and with each burner is associated a valve or cock by which the quantity of gas passing to 45 the burner may be regulated or the supply wholly cut off.

It is the principal object of the present invention to provide a burner in which the quantity of air admixed with the gas will be 50 in direct proportion to the quantity of gas allowed to pass through the burner, so that

thorough combustion is assured and the deposit of carbon prevented.

With this and other objects in view the invention consists in the novel construction and arrangement of parts hereinafter described, illustrated in the accompanying drawings, and particularly pointed out in the appended claims, it being understood that various changes in the form, proportions, and minor 55 details of structure may be made without departing from the spirit or sacrificing any of the advantages of the invention.

In the drawings, Figure 1 is a longitudinal sectional elevation of a burner-tip constructed in accordance with the invention, the drawings being made on an exaggerated scale. Fig. 2 is a sectional plan view of the burner on the line 2 2 of Fig. 1. Fig. 3 is a similar view on the line 3 3 of Fig. 1. Figs. 70 4 and 5 are views corresponding to Fig. 1, illustrating modified constructions of burners also embodying the invention. Fig. 6 is a side elevation, on a somewhat smaller scale, of a flat-flame burner embodying the invention. Fig. 7 is a plan view of the same.

Similar numerals of reference indicate corresponding parts throughout the several figures of the drawings.

The burner, or its tip, is formed of soap-stone, lava, or other refractory material and is provided with a centrally-disposed gas-passage 1, to which the gas is delivered from the supply-pipe.

In carrying out the invention the burner-tip is provided with a chamber graduated in diameter, being largest at the outlet, and with this chamber communicate a number of graduated air-ports, so that the quantity of air admitted will be in direct proportion to 85 the quantity of gas passing through the burner. As the gas is discharged under pressure and the height of the jet of gas is proportionate to such pressure the greater the pressure the larger the number of air-ports 90 which the jet will pass and the greater the quantity of air mingled therewith to produce the burning mixture.

In the construction shown in Fig. 1 the upper end of the tip is bored out to form a combustion-chamber 3, which communicates with the outer air through large openings 4, extend-

ing through the side walls of the tip. These openings 4 are so proportioned with respect to the diameter of the passage 1 as to admit a sufficient quantity of air to form a good burning mixture and support combustion when the full pressure of gas is turned on; but it is found when the pressure is excessive that the actual point of combustion, or the point at which the flame first becomes luminous, is at some little distance beyond and above the tip of the burner, this point varying in accordance with the pressure of the gas. The lower wall of the combustion-chamber 3 is bored out to form a mixing-chamber 5, the bottom of which communicates with the gas-passage 1. This mixing-chamber 5 is of much smaller area than the combustion-chamber 3 and is in communication with the outer air through correspondingly smaller passages 6, leading through the side walls of the tip and permitting under some circumstances the passage of air to the mixing-chamber in order to properly support the combustion at about the bottom of said combustion-chamber.

25 The gas passing through the channel or passage 1 if under extremely high pressure will slightly expand when it reaches the mixing-chamber 5 and will further expand as it passes through the chamber 3, retaining a jet-like form, which will draw with it a sufficient quantity of air to form a burning mixture and support combustion. The mixture of gas and air in part takes place within the chamber 5 and again in the chamber 3, air being admitted through the larger ports or openings 4 in the chamber 3 to effect the formation of a highly-inflammable gas. When the pressure is excessive, the mingled jet of air and gas will pass for some distance above and beyond the tip of the burner before the luminous portion of the flame is visible, and a portion of the air necessary to support combustion will be mixed with the gas above the top of the burner-tip. When the pressure is slightly checked, the supply of air furnished by the ports or openings 4 will be employed to support combustion; but should the flame be further reduced the quantity of air admitted to the openings 4 will be in excess of that required to support combustion, and under ordinary circumstances soot would immediately form and tend to choke the tip.

For reasons of economy it is desirable in many cases to lessen the consumption of gas by turning down the flame to as low a point as possible without extinguishing it, as is done in many cases in the consumption of ordinary coal-gas. This is found to be impossible in the commercial forms of acetylene gas-burners, for the reason that the quantity of air is much in excess of the quantity of gas and results in an accumulation of soot and choking of the tip. In the present case the small quantity of gas entering the mixing-chamber 5 mingles with atmospheric air entering through the radial passages 6, these

small passages being of sufficient size to admit just enough air to support combustion, while the flame may extend only in part to the combustion-chamber 3. Should the flame extend for any considerable distance in the chamber 3, the passages 6 will serve to assist the passages 6 in supplying the necessary air; but it is found by actual practice and extensive tests extending over a long period of time that it is practically impossible to deposit carbon in the form of soot at the tip, no matter what the quantity of gas consumed.

The walls of the combustion-chamber 3 serve as shields to prevent drafts of air from interfering with the smaller flame, so that it may not flicker or blow out, and this will prevent the entrance of free gas to the room or compartment in which the burner is situated, and these walls are of extensive area as compared with the area of the openings 4, so that a positive shield is formed and the compartment 3 may serve as a mixing-chamber when larger quantities of gas are passing through the burners.

It will be seen that the invention provides, in effect, a graduated chamber or a plurality of chambers of successively-increasing size and provided with successively-increasing ports or openings for the admission of air, so that when the quantity of gas is small the smaller chamber will serve practically as an initial combustion-chamber, and when the quantity grows larger the smaller chamber will act merely as a mixing-chamber, while combustion takes place either in whole or in part in the larger chamber, or, in other words, the jet issues from the mouth of gas-pipe 1 for a distance proportioned to the pressure and mingles with air entering through a larger or smaller number of ports to form a burning mixture. Above the point of initial combustion the oxygen of the air attacks the burning mixture in the usual manner.

Should the quantity of gas be excessive, both smaller and larger chambers serve as mixing-chambers, and actual combustion or at least the luminous flame resulting from combustion takes place outside of and beyond the burner-tip.

As the principal object of the invention is to properly proportion the quantity of air admixed with the gas in order to effect thorough and complete combustion, it is obvious that this mixing may be accomplished by burners of slightly-different construction, and in Figs. 4 and 5 are shown burners embodying the same principle, but differing slightly in the arrangement of the mixing and combustion chambers. In Fig. 4 there are shown three successive chambers of successively-increasing diameter and area, or these may be regarded as a single chamber of different diameter at different points. The smallest of these chambers 8 is next to the gas-passage 1 and is provided with a plurality of small air-entrances 8', and these will suffice to support

combustion where a very small quantity of gas is allowed to flow from the passage. When the quantity of gas is increased, the chamber 8 will serve merely as a preliminary mixing-chamber and the mingled gas and air will thus pass to the chamber 5 and be further admixed with air entering through the ports 6', the larger volume of gas requiring a proportionately larger volume of air to form a suitable burning mixture. Should the volume of gas be further increased, it will pass, together with the air, into the upper chamber 3 and there receive a further quantity of air, so that under all circumstances the burning mixture will be formed of properly-proportioned bodies of air and gas.

A burner of more simple construction and embodying the same principle is illustrated in Fig. 5, wherein the chamber 9 is funnel-shaped, being largest at the upper end of the tip, and communicating with this chamber at suitable intervals above the point of connection with the gas-pipe are a number of air-inlet ports 10. These ports successively increase in diameter in proportion to the distance from the outlet end of the gas-passage and in proportion to the cross-sectional area of the chamber at the points where they connect with such chamber. It will be observed that in this case also the passage of a small quantity of gas to the burner will result in the admixture therewith of but a small quantity of air, the air entering through the successive ports as the quantity of gas increases, so that when a suitable burning mixture has been formed the gas may be wholly consumed and disintegration and the deposit of carbon prevented. The point of combustion or of initial luminosity will automatically adjust itself in accordance with the pressure of the gas, so that there will be no danger of the gas passing upward to such an extent to mix with a larger quantity of air than is necessary to effect complete combustion. This invention might also be carried out in connection with burners of various forms; but in any case the burner must be so arranged as to proportion

the quantity of air to the quantity of gas to be consumed.

In lieu of increasing the diameters of the ports as their distance from the inlet-point increases the ports may remain of the same size and a larger number be used.

The construction described may be applied either to a single nipple-burner of the type shown in Fig. 1 or may be used for the flat-flame burners, wherein two separate jets impinge to form a flat or broadened luminous flame, this latter construction being shown in Figs. 6 and 7.

Having thus described the invention, what is claimed is—

1. A burner-tip having an orifice graduated in diameter and provided with graduated air-inlets communicating therewith at different distances from the outlet.

2. An acetylene-gas burner having a chamber of successively increasing diameter from its inlet to its outlet end, and air-inlet ports leading thereto at different points, said ports being constructed to admit successively larger quantities of air as their distance from the inlet end of the chamber increases.

3. An acetylene-gas burner having a chamber of successively increasing diameter from its inlet to its outlet end, and air-inlet ports leading thereto at different points, said ports being of successively larger diameter as their distance from the inlet end of the chamber increases.

4. A burner-tip having a tapering orifice of greatest diameter at the outlet and provided with air-inlet ports arranged at different distances from said outlet, the cross-sectional area of the ports being proportioned to the cross-sectional area of the orifice at the points at which they connect with such orifice.

In testimony that I claim the foregoing as my own I have hereto affixed my signature in the presence of two witnesses.
